UNITED STATES PATENT OFFICE.

FRANK H. CAVEN, OF PHILADELPHIA, PENNSYLVANIA.

DESIGN FOR FRINGE.

SPECIFICATION forming part of Design No. 23,001, dated January 2, 1894.

Application filed September 22, 1893. Serial No. 486,228. Term of patent 3½ years.

To all whom it may concern:

Be it known that I, FRANK H. CAVEN, a citizen of the United States, residing in Philadelphia, Pennsylvania, have invented a certain Design for Fringe, of which the following is a specification.

My design for a fringe is fully illustrated in the accompanying drawing.

The main feature of the design is a series of longitudinal bands connected together by cords, as fully illustrated in the accompanying drawing.

A is the heading. $\alpha\alpha'$ and α^2 are bands suspended therefrom by the cords b^1 and b^2 . The cords b are bunched at c and are tufted above the heading A. The cords b' are arranged at

angles and are formed into loops c' depending from the band a . The cords b^2 are bunched at c^2 and extend below the lower band a^2 , the whole giving the effect as fully shown in the accompanying illustration.

I claim—

The design for fringe as described and illustrated in the accompanying drawing.

In testimony whereof I have signed my name to this specification in the presence of two subscribing witnesses.

FRANK H. CAVEN.
